PROTECTIVE DIAL ASSEMBLY FOR PERMUTATION LOCKS

Harry C. Miller, Rochester, N. Y.

Application November 17, 1955, Serial No. 547,461

5 Claims. (Cl. 70—332)

The present invention relates in general to permutation locks, and more particularly to a dial and dial ring assembly for permutation locks affording security against detection by a distant observer of the combination used in opening the lock.

It has been long recognized that the combinations of permutation locks are subject to theft by unauthorized viewing of the successive registrations of the dial markings occurring during opening of the lock. Where such a lock is opened in the presence of other persons, it is a simple matter for such persons to note the combination from a point removed from the operator's position and thereafter gain unauthorized access to the closure secured by the lock.

Heretofore, various means have been provided to be used in connection with conventional combination lock dials, which shield the greater portion of the dial from view by unauthorized persons. These have generally taken the form of a shield or cover provided with a window exposing only a limited number of the dial markings to view along an axis perpendicular to the face of the dial. Such dial shields have the dual purpose of hampering observation of the dial numbers by persons to either side of the operator while the operator is dialing the combination, and limiting the range of exposed dial markings which are visible so that the body of the operator will shield the exposed dial area from observation by persons at remote locations to the rear of the operator. These dial shields, however, are usually in the form of additional accessories which must be associated with the combination lock and dial, and in many cases afford such a limited visible dial area that the lock dial must be operated very slowly in order to bring the proper numbers on the dial into registry with the index mark. Also, because of the restricted visible dial area, the numbers are often so obscured or difficult to count that the operator must make a number of attempts before the successful combination is dialed.

Another disadvantage of circular dial type combination locks, whether they are provided with dial shields or not, is that the dial and dial ring are uniformly formed of opaque material, so that the area of the safe or file cabinet wall immediately behind the dial and dial ring is not visible. It is not an uncommon practice for persons who are seeking unauthorized admission to the safe or file cabinet to open the lock by drilling a hole through the dial, the dial ring and the safe or file cabinet wall, into the lock housing, at a point such that an instrument can be inserted into the lock housing to retract the bolt. In such instances, if the person then replaces the drilled opaque dial with an identical dial, it is not apparent thereafter that the lock has been tampered with.

An object of the present invention, therefore, is the provision of a novel dial and dial ring assembly for combination locks, which effectively prevents unauthorized viewing of the dial markings as they are moved into registration with the index mark, without materially im-

2

pairing or interfering with the operator's vision of the markings.

Another object of the present invention is the provision of a novel dial assembly for combination locks constructed in such a manner that the surface area on which the dial assembly is supported is visible through the dial, thereby discouraging unauthorized actuation of the lock by drilling through the dial supporting body.

Another object of the present invention is the novel construction of a dial assembly for combination locks, in which visibility of the dial markings to persons other than the operator is severely restricted and any apertures drilled through the dial supporting body to gain unauthorized admission to the lock are exposed to view.

Other objects, advantages and capabilities of the present invention will become apparent from the following detail description, taken in conjunction with the accompanying drawings, wherein only a preferred embodiment of the invention is illustrated.

20 In the drawing:
Figure 1 is a front elevation of a dial assembly for combination locks embodying the present invention, illustrated on a fragmentary portion of a safe door;

Figure 2 is a vertical transverse section view taken along the lines 2—2 of Figure 1;

Figure 3 is a top plan view of the dial assembly; and

Figure 4 is a perspective of the annular shield insert employed in one embodiment of the present invention.

Referring to the drawing wherein like reference characters designate corresponding parts throughout the several figures, the combination lock dial assembly, designated generally by the reference character 10, is adapted to be mounted in the conventional manner on a closure panel 11 such as a safe door, a file cabinet drawer wall, or the like, and to be secured to the lock actuating spindle 12 projecting forwardly of the closure panel through a suitable aperture 13 therein from a combination lock casing 14 mounted on the inner surface of the closure panel. The combination lock casing 14 and the lock components may be of any conventional construction, such as that disclosed in my earlier United States Patent No. 2,575,674, granted November 20, 1951.

The dial assembly 10 includes a circular dial 15 of Lucite or other transparent plastic material having a planar rear surface 16, a peripheral surface 17 of sufficient width to accommodate dial markings or other indicia thereon, and a front surface 18 in the form of a conical annulus extending from a maximum spacing relative to the rear surface 16 at the periphery of the dial to a minimum spacing at its inner end. At the inner end of the annular front surface 18 is an annular shoulder portion 19 supporting a dial knob 20 of truncated conical form, which may be of plastic material molded or milled integral with or separate from the dial 15, or a metallic knob affixed to the dial 15. The knob 20 is provided with an axial cylindrical bore aligned with an aperture 21 in the dial 15 to be fitted upon the end of the lock spindle 12 for imparting rotation to the spindle 12.

60 A dial ring 22 is assembled with the dial 15, and in accordance with conventional practice, is in the general form of a circular body of greater diameter than the dial 15 having a disc-shaped backing portion 23 adapted to be secured to the closure panel 11 between the panel 65 and the dial 15 and an annular flange portion 24 forming an encasing surround for the periphery of the dial 15 and projecting outwardly beyond the front surface 18 of the dial. The annular flange portion 24 of the dial ring 22 is of substantially right triangular cross-section having a cylindrical inwardly disposed wall 25 concentric with and spaced slightly from the periphery 17 of the dial 15, an annular front surface 26 at right angles there-

to and an outer surface of revolution 27 inclined rearwardly from the surface 26 and outwardly from the axis of the dial ring. The dial ring 22 is preferably formed from one of the methyl methacrylate or polystyrene resins such as Lucite, Plexiglas, and the like, by milling or molding the same into the desired shape.

An opaque split ring shield member 28 is adapted to be inserted between the periphery 17 of the dial 15 and the inner wall 25 of the dial ring 22 and resiliently held against the wall 25 in surrounding relation to the dial periphery 17. This shield member 28 is constructed of sheet metal deformed into an annulus of greater diameter than that of the dial ring wall 25 and compresses a band of the width of the inner wall 25 of the dial ring 22 over the major portion of its length having a relieved area 29 forming a sight opening disposed intermediate the ends of the shield member 28. The relieved area is bounded along one edge of the shield member 28 by a connecting strip 30 having a pointer formation 31 intermediate the shoulders 32 laterally bounding the relieved area 29 and narrowed sections 33 extending from the pointer 31 substantially half way to the shoulders 32 forming resilient arms to facilitate manual flexing of the split ring shield member.

The shield member 28 is designed to be manually sprung to assume a diameter slightly smaller than that of the inner wall 25 of the dial ring 22 so that the shield may be inserted into the dial ring and released to assume a position against the inner dial ring wall 25 and frictionally maintained in such position by the sprung condition of the shield member 28.

If desired, the shield member 28 may be dispensed with by merely frosting the inner wall 25 of the dial ring 22 in a pattern rendering the dial ring 22 translucent only over the region that would otherwise have been shielded by the shielding member 28.

The dial graduations or markings, indicated at 34 are incised as by etching, milling, or the like, into the periphery 17 of the dial 15 and are then filled with stick paint or like opaque material. In the preferred embodiment, a paint of a color which blends with the color of the dial 15 is first applied to the surfaces of the incised dial markings 34, and this blending color is then overlaid with a paint of a contrasting color. In this way, the dial markings facing observation points exterior to the dial are rendered readily visible, while the dial markings on the opposite portion of the dial periphery are rendered substantially indistinguishable.

By the construction herein described, the dial markings 34 on the periphery 17 of the dial 15 are visible through only a very limited sector above the dial 15 when the dial assembly is mounted on a closure panel. The limited range of visibility transversely of the closure panel prevents detection of the dial markings by persons stationed to the side of the operator during manipulation of the dial by an authorized person. Further, the dial ring flange 24 provides a light refracting body disposed relative to the dial markings to pass only those light rays reflected from the dial markings which emerge from the ring along axes inclined at small angles to the plane of the dial 15 and distort or internally reflect light rays inclined at large angles to the dial 15 in excess of fifty or sixty degrees. The optical characteristics of the dial ring 28, therefore, so restrict the angles of emergence of light rays as to render the dial markings visible only from positions directly above and extending only a few feet outwardly from the closure panel. As this area coincides substantially with that occupied by the head of an operator when the operator stands at the usual position of address to the dial, the positions to the side of or behind the operator from which the combination being dialed could be observed by unauthorized persons is so restricted as to effectively preclude breach of security of the lock in this manner.

While but one preferred embodiment of the invention has been particularly shown and described, it is apparent that various modifications may be made without departing from the spirit and scope of the invention, and it is desired, therefore, that only such limitations shall be placed thereon as are set forth in the appended claims.

I claim:

1. In a dial assembly for permutation locks, a rotatable circular dial having a cylindrical periphery and dial markings on said periphery, a circular dial ring of transparent material adapted to be fixed to a supporting surface in coaxial underlying relation to said dial and having an uninterrupted annular peripheral flange projecting in encircling concentric slightly spaced relation with the periphery of said dial, said dial ring flange terminating forwardly in a planar annular surface lying in a plane normal to the axis of said dial and to said cylindrical periphery and spaced outwardly of said dial periphery and arranged to prevent transmission through said annular surface of distinguishable images of said dial markings along axes lying forwardly of the plane of said dial and means rendering said dial markings distinguishable through only a limited arcuate segment of said flange.

2. In a dial assembly for permutation locks, a rotatable circular dial having a cylindrical periphery and dial markings on said periphery, a circular dial ring of transparent material adapted to be fixed to a supporting surface and coaxially mounted relative to said dial in underlying relation therewith, said dial ring terminating peripherally in an uninterrupted annular flange projecting in encircling concentric relation with the periphery of said dial, said annular flange having an inner cylindrical surface conforming closely to the periphery of said dial, an outer surface spaced radially outwardly of said inner surface, and a planar annular surface lying in a plane substantially normal to said inner cylindrical surface and spaced forwardly from said dial periphery interconnecting said outer and inner surfaces at the forward edges thereof to internally reflect the image-forming rays emanating from said dial markings along axes inclined at large angles to the plane of said dial for limiting transmission of distinguishable images of said dial markings to a small angle spherical sector extending about the axis of said dial, and shield means rendering said flange non-transparent to said dial markings over the major portion of said dial periphery and providing a sight area through which said dial markings are visible over a limited arcuate segment of said flange.

3. In a dial assembly for permutation locks, a rotatable circular dial of transparent material having a cylindrical periphery and dial markings immediately adjacent the forward edge of said periphery, a circular dial ring of transparent material coaxially mounted relative to said dial having a base adapted to be fixed to a supporting surface and interposed between said dial and said surface and an uninterrupted annular peripheral flange integral with said base projecting forwardly from said base in encircling concentric relation with the periphery of said dial, said flange having an inner cylindrical surface conforming substantially to the diameter of said dial, an outer surface of revolution concentric with said inner cylindrical surface and spaced radially therefrom, and a planar annular surface lying in a plane normal to said inner cylindrical surface and spaced forwardly from the front edge of said dial periphery interconnecting the forward edges of said inner cylindrical surface and said surface of revolution and forming an internal reflecting surface for image-forming rays from said dial markings propagated along axes subtending small angles with the axis of said dial to confine emergent distinguishable images of said dial markings to the space between the rearmost plane of said dial and a cone of revolution about the axis of said dial whose elements form small angles with said rearmost plane, and shielding means for shielding

said dial markings against observation through said flange over the portions of said flange complementary to a limited arcuate segment thereof.

4. The combination recited in claim 2, wherein said circular dial and said circular dial ring and dial ring flange are constructed of Lucite.

5. In a dial assembly for permutation locks, a circular dial having a cylindrical periphery and dial markings on said periphery, a circular dial ring of transparent material adapted to be fixed on a supported surface and having a disc portion and an integral, uninterrupted peripheral flange portion projecting from said disc portion and defining therewith a forwardly opening cylindrical bore of greater depth than the width of said dial periphery encircled by said flange portion, said dial being rotatably disposed in said bore in concentric relation to said flange with said dial periphery wholly underlying said flange, and said peripheral flange portion terminating forwardly in a planar, annular surface lying substantially normal to the plane of said cylindrical periphery and spaced forwardly therefrom, a removable shielding member comprising a split annular band of sheet metal of a width

corresponding to the depth of said bore and of greater diameter than said bore, said band having a relieved intermediate region forming an aperture for inspection of a limited arcuate segment of said dial periphery through said flange bounded along an edge of said band by an integral connecting strip having a centrally disposed indexing projection and narrowed highly resilient regions extending oppositely therefrom, whereby said annular band may be sprung to a reduced diameter for insertion between said flange and dial periphery and resiliently retained against said flange in tensioned condition.
